UNITED STATES PATENT OFFICE.

WILLIAM H. REES, OF NEW YORK, N. Y.

AUTOMATIC TEMPO-REGULATOR.

1,032,624.

Specification of Letters Patent. Patented July 16, 1912.

Application filed April 27, 1912. Serial No. 693,611.

To all whom it may concern:

Be it known that I, WILLIAM H. REES, a citizen of the United States, and a resident of New York city, borough of Manhattan, in the county of New York and State of New York, have invented certain new and useful Improvements in Automatic Tempo-Regulators, of which the following is a specification.

10 This invention relates to new and useful improvements in automatic tempo regulators, for use in connection with the air motors for moving perforated music sheets in playing attachments for musical instruments.

15 The object of this invention is to provide a new and improved automatic tempo regulator for the above purposes which is simple in construction, and which is capable of changing the speed of the air motor, from faster to slower or slower to faster, either slowly or suddenly as may be necessary, in a reliable and effective manner.

20 In the accompanying drawings in which like letters of reference indicate like parts in all the figures: Figure 1 is a longitudinal sectional elevation of my improved automatic tempo regulator in connection with the motor for moving the music sheet and the controlling valve for this motor. Fig. 2 is a vertical transverse sectional view through the tempo regulator and through the valve mechanism for the same and the tracker board. Fig. 3 is a plan view of part 35 of the tracker and part of the perforated music sheet, parts being broken out and others shown in section.

25 The motor 1 for moving the perforated music sheet is an air motor and may be of any conventional construction provided with a crank shaft 2 and a series of motor bellows 3 for operating the crank shaft. From the crank shaft 2 the power is transmitted to the perforated music sheet rolls 45 or spools in any well known manner. Air is exhausted from the bellows of this motor through a tube 4 into the valve chest 5 and from the latter into an exhaust tube 6 and the opening from the chest 5 to the tube 6 can be adjusted to any size by a slide valve 7 in the valve casing, so that by moving the slide valve to the left the effective area for the passage of air is increased and the motor caused to run faster, and by moving

the valve to the right the effective area is decreased and the motor is caused to run slower. The parts so far described are also well known and are generally used in playing attachments.

30 On a base plate 8, two sets of standards 9 are mounted and in said four standards two parallel screws 10 are mounted, and each screw carries a cog wheel 11, which cog wheels are engaged thus compelling the screws to rotate in opposite directions. 35 One of the screws carries at its end a sprocket wheel 12 or other power transmitting contrivance for the purpose of rotating said screw from a small pneumatic or other motor 13 which runs at uniform speed. A 40 rod 14 is mounted on grooved rollers 15 on the base plate 8 so as to permit of moving this rod lengthwise with as little friction as possible. One end of this rod is pivotally connected with a lever 16 pivoted at 17 and 45 connected at its opposite end with a rod 18 attached to the previously mentioned valve 7 so that as this rod 14 is moved lengthwise in one direction or the other the valve 17 is moved correspondingly. A hub 19 is secured on the rod 14 and from the same an arm 20 projects upward and to said arm a T-shaped yoke 21 is pivoted at 22 and is provided in the lower end of its upright member with a recess 23 for receiving the 50 upper end of a spring 24 secured at 25 to the arm 20 of the hub 19, so that this spring will normally hold the vertical member 22 of the yoke 21 in vertical alinement with the arm 20. The yoke is provided in each 55 arm at 26 with a threaded nut portion which can engage the corresponding screw 10 below it, but which nut portions are normally out of engagement with the screw when the vertical member of the T-shaped yoke is in 60 perfect alinement with the arm 20. The outer end of each arm of the yoke 21 is connected by a rod 27 with the movable board 28 of a pneumatic 29, which pneumatics are secured on rods 30 which run on grooved 65 rollers 31 on the base plate 8. The rods 30 and rod 14 are connected by cross pieces 32 so that the rods 30 and 14 travel uniformly in the direction of their length in either direction. Each bellows 33 is connected by a 70 flexible tube 34 with a valve casing 35 containing a controlling valve 36 which is operated from a diaphragm 36, the chamber

of which is connected by a tube 37 with a duct 38 or 39 in a tracker board 40 over which the perforated music sheet 44 passes. There being two valves 35 two tracker ducts 5 38 and 39 there are two rows 41 and 42 of perforations in the music sheet. As long as the paper covers the holes 38 and 39 the valves 35 keep the bellows 29 open to the atmosphere and the bellows are expanded 10 and both ends of the yoke 21 are raised, that is, the yoke is held in such position that neither of the two screw parts 26 is engaged with the screw below it and consequently the yoke and the parts connected therewith 15 are at a standstill and the valve 7 controlling the air motor for the musical instruments retains its position.

If the speed of the motor 3 is to be increased, a hole in the row 41 of the note 20 sheets is provided and when this hole or slot registers with the duct 38 air passing through the conduit 37 and acting on the diaphragm 36 seats the valve 35 and the right hand pneumatic 29 is now exhausted 25 and pulls down the right hand end of the T-shape yoke 21 against the tension of the spring 24 and engages the right hand screw part 26 of the yoke with the corresponding screw and this causes a movement of the 30 yoke, the rods 14 and 30 to the right, whereby the controlling valve 7 of the motor 3 is opened to a greater extent and such engagement of the part 26 with the screw as described above continues for the length of 35 time that the slot 41 registers with the duct 38, that is to say, the greater the length of the slot 41, the greater will be the movement of the valve 7 toward the open position. When the end of the slot 41 arrives 40 at the duct 38 the valve 35 is moved outward by suction, permitting air to pass into the right hand bellows 29, which expands, permitting the spring 24 to throw the yoke into normal disengaged position. In this 45 manner the valve 7 can be opened for a greater or less distance and remains in the position into which it has been adjusted until one of the screws is again engaged with a threaded part of the T-shaped yoke 21. 50 When the speed of the motor is to be decreased a hole or slot in the row 42 is brought into engagement with the tracker duct 39, and the left hand screw part 26, on the yoke, is engaged with the left hand 55 screw, and this causes the movement of the two shafts 14 and 30 with the yoke to the left, for a greater or less distance corresponding to the length of the slot in the music sheet, and thereby the valve 7 is 60 moved a greater or less distance toward the closed position and remains in such position after the slot or hole 42 has come out of register with the duct 39, and so remains until by the registering of one of the holes

of the rows 41 or 42 in the note sheet with 65 one of the tracker ducts 38 or 39 the rod 14 connected with the valve 7 is again shifted in one direction or the other.

Having described my invention what I claim as new and desire to secure by Letters 70 Patent is:—

1. The combination with a motor and its controlling valve, of two screws, means for rotating them in opposite direction, a member capable of engagement with either 75 screw, and means for operating said motor controlling valve from said member, substantially as set forth.

2. The combination with a motor and its controlling valve, of two screws, means for 80 rotating them in opposite directions, a member capable of engagement with either screw, and pneumatic means for engaging said member with either screw, and means for operating said controlling valve from 85 said member, substantially as set forth.

3. The combination with a motor and its controlling valve, of two screws, means for rotating them in opposite directions, a member capable of engagement with either 90 screw, means for operating the motor controlling valve from said member, and pneumatic means for engaging said member with either screw, and means for controlling said pneumatic means from a perforated music 95 sheet, substantially as set forth.

4. The combination with a motor and its controlling valve, of two parallel screws, means for rotating said screw in opposite directions, a member capable of engagement 100 with either screw, a connection between said member and the motor controlling valve, two pneumatic mechanisms for shifting the member to be engaged with the screws, and means for controlling said pneumatic motor 105 mechanism from a perforated music sheet, substantially as set forth.

5. The combination with a motor and its controlling valve, of a longitudinally movable rod connected with said valve, two 110 parallel screws, means for rotating them in opposite directions, a shiftable yoke carried by the rod connected with the motor controlling valve, and means for shifting said yoke for connection with either screw, and 115 pneumatic means controlled by the music sheet for operating the means for shifting the yoke, substantially as set forth.

6. The combination with a motor and its controlling valve, of a longitudinally movable 120 rod connected with the valve, two parallel screws, means for rotating them in opposite directions, and an arm carried by the rod connected with the motor valve, a yoke pivoted on said arm and having two threaded 125 parts adapted to be engaged with the screws, a spring for holding said yoke in normal position disengaged from the screws,

two pneumatic means for engaging either end of the yoke with a screw, and means for controlling said pneumatic means from the perforated music sheet, substantially as set forth.

- 5 7. The combination with a motor and its controlling valve, of a rod mounted to move longitudinally and connected with the valve, a rod at each side of the above mentioned 10 rod, cross pieces connecting the three rods, an arm on the middle rod, a yoke pivoted on said arm and provided with two screw threaded portions, two parallel screws adapted to be engaged with the yoke, means 15 for rotating the screws in opposite directions, a pneumatic carried by each side rod, a connection from each pneumatic to the yoke, a controlling valve for each pneumatic and means for operating the control-

ling valve from a perforated music sheet, 20 substantially as set forth.

8. The combination with a motor and its controlling valve, of a rod connected with the controlling valve, two devices for moving said rod in opposite directions, pneumatic means for connecting the rod with either one of said devices and means for controlling the operation of said pneumatic means from a tracker by means of a perforated music sheet.

Signed at New York city, in the county of New York and State of New York this 8th day of Apr. A. D. 1912.
